Specification of Letters Patent.

Patented Jan. 27, 1914.

Original application filed May 15, 1907, Serial No. 373,849. Divided and this application filed July 10, 1911.
Serial No. 637,759.

To all whom it may concern:

Be it known that I, EDWARD B. HESS, a citizen of the United States of America, residing in the borough of Manhattan, city, county, and State of New York, have invented a certain new and useful Improvement in Writing-Machines, of which the following is a specification.

This invention comprises a new line-lock organization hereinafter set forth in detail.

In the accompanying drawing: Figure 1 is a vertical longitudinal section of so much of a front strike typewriting machine as is deemed desirable to illustrate the invention; Fig. 2, a rear elevation; Fig. 3, a plan; Fig. 4 a rear elevation of margin stop device; and Fig. 5 shows a modification.

X and Y indicate the side or end plates of a carriage of which S is the rack bar and S' the ordinary cylindrical platen mounted to turn in the end plates. In rear of the platen, there is mounted in the end plates a transversely disposed bar N having co-incident and equally spaced teeth on its upper and rear surface. On this bar are adjustably mounted right and left hand margin stops K, and also intermediate adjustable stops M that may be used for tabulation purposes.

J is a center or frame stop pivoted upon the frame at j and adapted to be moved transversely of the toothed bar N.

In the particular construction illustrated, the center stop J is so arranged as to be out of the path of the tabular stops M but in the path of the margin stops K. The stops M are bifurcated and closely fit in the spaces between the upper and side teeth of the rack bar. The margin stops may each be constructed as follows: Each has a pivoted spring latch K², adapted to engage the spaces between the teeth on the upper surface of the bar N, pivoted on a stop frame K³ that straddles the rack bar and is held in position thereon by cross pins k extending beneath the bar between lugs on opposite sides of the frame. The part of the stop against which abuts the frame stop J is the head k' of an adjustable screw turning in a threaded opening in a lateral projection or block on one side of the frame K³ and having applied to its threaded end a lock nut k². A beveled plate k³ carried on the upper surface of the projection in which the screw is mounted serves to snub the stop lever out

of the way when the carriage is moved in one direction whereas the stop lever J is engaged by the head k' when the carriage moves in the other direction. The stop lever J is shown as a straight lever and below its pivot it fits between the arms of a rocking bifurcated arm O fast on a rock shaft O' pivoted in the frame of the machine and having at its right hand end an upright projection O² attached by a link O³ to a vertically disposed lever arm O⁴ located at the right hand side of the key board of the machine. Springs o, o, bearing respectively upon opposite sides of the vertically disposed bifurcated part O tend to maintain it in central or vertical position. Above the pivot j of stop lever J, the latter has an adjustable screw o' that engages the lower end of a rack releasing lever I, whose upper end lies under a horizontal flange of the escapement or feed rack S. This rack is carried in the ends of levers s s pivoted at s' on the side plates of the carriage and having applied to their ends springs s² the reaction of which tends to hold the rack in engagement with the pinion S² of the escapement devices. When lever arm O⁴ is drawn to the front, the upper end of stop lever J is rocked away from the stop bar N. This movement is of such extent as to disengage the lever J from the part k' of the margin stop to thereby permit of the writing of one or more letters at the end of a line. When lever arm O⁴ is pressed rearwardly, the upper end of lever J will be swung toward the intermediate or tabular stops and this occurs to such extent as to cause such lever to engage a stop M on the stop bar. In tabulating work this movement causes lever I to disengage rack S from the escapement pinion S² so that the carriage will run free until arrested at tabular stop M engaging the frame stop J. Fig. 5 shows the use, in lieu of the rocking lever O⁴, of a bifurcated lever O⁵ pivoted intermediate its ends at O⁶ and to the lower end of which is jointed the link rod O³. The two upwardly extending arms standing respectively in front and rear of the pivot are provided with finger pieces O⁷, O⁸. When lever O⁴ or either finger piece O⁷ or O⁸, is released the parts all tend to return to normal position under the influence of the controlling springs.

Pivoted at p on the right hand side of

2

stop lever J at a suitable point above the pivot j of the latter is a plate P whose axis p is at right angles to axis j . This plate extends upwardly substantially as far as the stop lever J and is normally held away from the latter by re-action spring p' . An extension P' from plate P extends a suitable distance below its pivot and is connected by link P^2 with a radial arm Q on the upper end of a vertical rock shaft Q' having near its lower end a radial arm Q^2 from which extends forward a link Q^3 connected at its front end with a radial arm q' on a transverse rock shaft q . This rock shaft q has extending upward from it a key lever locking plate q^2 which normally is inclined slightly forward from a vertical line. The flat key levers of the machine are of the class that are pivoted at their rear ends and extend horizontally forward to the key board where their upturned ends, standing in different rows or banks as usual, are equipped with finger pieces. They are all of the same character and the drawing shows but one, marked R, which is one of the shorter levers having its finger piece in the rear bank or row of the key board. Adjacent the front ends of the shorter key levers is a fixed vertical transverse slotted plate X, ordinarily called a guide comb, in the slots of which play and are guided the flat key levers. At or adjacent this comb the under faces of the key levers are formed with locking surfaces r which are in line transversely of the machine. Such locking surfaces form the lower edges of widened parts of the key levers that fit in the slots of the guide comb X. At one end of each locking surface, the front end as shown, there is a clearance space r' opposite or beneath which stands the upper edge of the locking plate q^2 , where it is normally held by a reaction spring q^3 . When the stop J P is engaged by either a margin stop or a tabular stop as the carriage is moving during the progress of the printing operation or is jumped for tabulation, plate P will be carried against the side of stop J and in its movement will effect a movement of rock shaft q that will carry the locking plate q^2 under the locking surfaces r on the key levers and positively and firmly lock them against depression.

The line locking or key lever locking plate q^2 normally standing in an upright position although slightly inclined to the front does not interfere with depression of the key levers for printing because of the clearance space r' . A very slight forward movement of the locking plate q^2 however causes it to pass under the surfaces r at the front edges thereof. The movement required need be but a small fraction of a letter space and may be readily obtained by the devices described or in other appropriate ways. When

by the means described, or in other appropriate ways, the frame stop is disengaged from the carriage stop, the keys are coincidentally unlocked.

It is known that heretofore various means for locking key levers both above and below the same have been proposed. The construction herein described is characterized by the following novel features: (a) the key levers are pivoted at their rear ends and the rigid locking plate acts against their under faces adjacent their finger piece ends: (b) the locking plate is applied to the under faces of the key levers contiguous to the guide comb which is located adjacent the finger piece ends of the levers. These features have the advantage that when the finger piece of a locked lever is struck the blow is received upon the rigid locking blade contiguous to the guide comb and near the finger piece end, with the result that there is no bending or distortion of the lever and no lateral displacement thereof.

The invention is shown applied to a front strike machine. It is, however, not restricted to machines of that type.

This application is a division of my application filed May 15, 1907, Ser. No. 373,849.

I claim:

1. In a typewriting machine, the combination of horizontally disposed flat key levers pivoted at their rear ends and each formed with a locking surface on its lower edge adjacent its front end with a clearance space at the end of the locking surface, all said locking surfaces being arranged opposite each other transversely of the machine, a key lever locking member arranged below said clearance space and in juxtaposition to the locking surface, a carriage adapted to be moved step by step transversely of the machine, a stop carried by the carriage, a cooperating stop on the frame, an operative connection between the latter and said locking member, said connection extending from the rear of the machine forward to said locking member, whereby when the two stops come in contact said locking member is moved beneath the locking surfaces of the key levers to lock them against depression and means under the control of the operator for unlocking the key levers to permit their actuation.

2. In a typewriting machine, the combination of horizontally disposed flat key levers pivoted at their rear ends and each formed with a locking surface on its lower edge adjacent its front end with a clearance space at the end of the locking surface, all said locking surfaces being arranged opposite each other transversely of the machine, a transversely disposed guide comb in the slots of which the flat key levers are guided at or adjacent the parts thereof having said locking surfaces, a key lever locking mem-

ber arranged below said clearance space and in juxtaposition to the locking surface, a carriage adapted to be moved step by step transversely of the machine, a stop carried by the carriage, a coöperating stop on the frame, an operative connection between the latter and said locking member whereby when the two stops come in contact said locking member is moved beneath the locking surfaces of the key levers to lock them against depression and means under the control of the operator for unlocking the key levers to permit their actuation.

3. In a typewriting machine, the combination of horizontally disposed flat key levers pivoted at their rear ends and each formed with a locking surface on its lower edge adjacent its front end with a clearance space at the end of the locking surface, all said locking surfaces being arranged opposite each other transversely of the machine, a transversely disposed guide comb in the slots of which the flat key levers are guided at or adjacent the parts thereof having said locking surfaces, an upwardly extending pivoted locking plate whose upper edge lies beneath said clearance space, is closely adjacent said locking surfaces and is movable to a position under said locking surfaces, a carriage adapted to be moved step by step transversely of the machine, a stop carried by the carriage, a coöperating stop on the frame, an operative connection between the latter and said pivoted locking blade whereby when the two stops come in contact, said pivoted locking blade is moved beneath the locking surfaces of the key levers to lock them against depression and means under the control of the operator for unlocking the key levers to permit their actuation.

4. In a front strike typewriting machine, the combination of horizontally disposed flat key levers pivoted at their rear ends and each formed with a locking surface on its lower edge adjacent its front end with a clearance space at the end of the locking surface, all said locking surfaces being arranged opposite each other transversely of the machine, a transversely disposed guide comb in the slots of which the flat key levers

are guided at or adjacent the parts thereof having said locking surfaces, an upwardly extending pivoted locking blade whose upper edge lies beneath said clearance space and is movable to a position under said locking surfaces, a carriage adapted to be moved step by step transversely of the machine, a stop carried by the carriage, a coöperating stop on the frame comprising a vertically disposed rocking lever part, a horizontally disposed link extending rearwardly from said pivoted locking blade and an operative connection between said vertically disposed lever part and said link whereby when the two stops come in contact the locking blade is moved under the locking surfaces of the key levers to lock them and means under the control of the operator for unlocking the key levers.

5. In a typewriting machine the combination of horizontally disposed key levers pivoted at their rear ends and each formed with a locking surface on its lower face adjacent its front end with a clearance space at one end of the locking surface, all such locking surfaces being arranged opposite each other transversely of the machine, a carriage adapted to be moved step by step transversely of the machine, a cylindrical platen mounted in the carriage, a stop carried by the carriage in rear of the platen, a coöperating stop mounted on the frame in rear of the platen, a key lever locking member normally disposed under the key levers and beneath said clearance space therein and adapted to be moved under the locking surfaces to lock all the key levers against depression and an operative connection extending forward from the stop on the frame to the key lever locking member whereby the latter is moved to locking position when said stop and the stop on the carriage come in contact.

In testimony whereof, I have hereunto subscribed my name.

EDWARD B. HESS.
